UNITED STATES PATENT OFFICE.

JACKSON H. DUNLAP, OF TURLOCH, ASSIGNOR OF ONE-HALF TO WILLIAM WILKINSON, OF LOS GATOS, CALIFORNIA.

TANK-SPOUT.

SPECIFICATION forming part of Letters Patent No. 268,467, dated December 5, 1882.

Application filed August 26, 1882. (No model.)

To all whom it may concern:

Be it known that I, JACKSON H. DUNLAP, of Turloch, county of Stanislaus, State of California, have invented an Improved Tank-Spout; and I hereby declare the following to be a full, clear, and exact description thereof.

My invention relates to an improved water-spout specially adapted for railway-tanks, from which the locomotive-tender is supplied with water.

My invention consists in a spout having two hinge-joints, one of which adapts it for a horizontal or lateral adjustment and the other for a vertical adjustment; and it also consists in the peculiar construction of said joints, whereby the adjustment is accomplished and a water-tight connection preserved.

The object of my invention is to provide for the ready and accurate adjustment of the spout to the locomotive-tender.

The spouts now in use are adapted to be turned up or down, but have no lateral adjustment, so that it becomes necessary to move the engine several times before its tender is finally brought in a position to receive the spout. This difficulty I overcome by combining in a spout a means for obtaining the two necessary adjustments—namely, vertical and lateral—so that the engine may stop within a convenient distance and the spout be at once fitted to its tender without having to move again.

Referring to the accompanying drawings, Figure 1 shows a view of the spout with its two hinge-joints. Fig. 2 is a longitudinal section, and shows the construction of the upper or horizontally-adjusting joint. Fig. 3 is also a longitudinal section, and shows the construction of the lower or vertically-adjusting joint.

In Fig. 1, let A represent a portion of an ordinary water-tank, which may be supposed to be beside a railway-track. Through its bottom a discharge-opening is made, which, upon the inside, will be controlled by a suitable valve, which itself will be operated by appropriate levers, none of which devices will be shown here.

B is a sleeve having a flange, b, at its top, by which it is bolted to the bottom of the tank A under the discharge-opening. This sleeve has an inwardly-extending shoulder, a,

and its lower end is cut out at c, as shown in Fig. 2. Within this sleeve B is a pipe, C, having a flange, d, at its top, which fits over and upon the shoulder a of the sleeve and secures the pipe therein, though allowing it to turn freely. The lower end of this pipe extends beyond the end of the sleeve B, and is threaded, as shown.

D is the packing nut or ring. This consists of a small piece of pipe forming a body and a flange or rim, as shown. The body extends up between the sleeve B and pipe C in the cut-out end c of the former. This nut is screwed upon the inner pipe C, and fits closely up against the end of the sleeve B. Upon the end of pipe C is screwed an elbow, E, fitting tightly against the face of nut D. A pipe, F, is screwed into this elbow, and extends horizontally. By this construction the pipe F may be turned laterally, as the inner pipe C and the packing nut or ring D both turn within the sleeve B, and at the same time preserve a perfectly water-tight joint. The outer end of pipe F receives a T-shaped coupling marked G, the arms of which are horizontal or nearly so. The ends of these arms are cut out at c', as shown. Within the arms of this T-shaped coupling, extending through and projecting at each end, is a pipe, H, having a side opening, h, at its center, and threaded ends which receive packing nuts or rings I, similar to nut D above. These nuts screw onto the pipe H, and extend with the T-shaped coupling in its cut-out ends c', its face or flange fitting up against the ends of the T-shaped coupling as closely as desired.

Upon the projecting ends of the pipe H are screwed curved elbows K, which receive pipes J in their other ends. These pipes converge to an elbow, L, from which extends a curved pipe or nozzle, M.

It will be observed that after leaving the elbows K, I could have two parallel pipes with suitable unions and elbows, finally ending in a single one; but I show this construction as being cheaper and lighter.

I can raise or lower the end pipe or nozzle, M, for the inner pipe H and the packing-nuts I turn in the T, and still make a water-tight joint.

By placing washers wherever needed between the meeting ends of the pipes the joints may be made as close and tight as desired.

The advantage of this device will be seen in a description of its operation. Suppose the spout to be suitably hung up out of the way. The locomotive comes to a standstill at some distance beyond the tank. Ordinarily it would have to back to stop opposite to the spout; but in this case the fireman releases the spout, turns it forward on its upper hinge-joint to a line with water-receptacles, and then pulls it down on its lower hinge-joint to fit its end pipe or nozzle into the hole. Therefore within the limit of its reach it may be adjusted up or down the track, and may be raised or lowered with accuracy and facility.

Having thus described my invention, what I claim as new, and desire to secure by Letters Patent, is—

1. In combination with a water-tank, a spout connected therewith, said spout having a vertical hinge-joint, whereby it may be moved and adjusted laterally, and a horizontal hinge-joint, whereby it may be moved and adjusted vertically, substantially as and for the purpose herein described.

2. In combination with a tank, A, a vertical hinge-joint consisting of the sleeve B, bolted to the tank at its discharge, and having a shoulder, *a*, and a cut-out end, *c*, the inner pipe C, having a flange, *d*, fitting shoulder *a*, and a threaded end, and the packing nut or ring D, screwed upon pipe C, and fitting within and against the cut-out end of sleeve B, the 35 elbows E screwed to the end of inner pipe C, the pipe F, the horizontal hinge-joint, consisting of the T-shaped coupling G, having cut-out ends *c'*, the inner pipe H, having a side opening, *h*, and threaded ends, and the packing 40 nuts or rings I, screwed upon the ends of pipe H, and fitting within and against the cut-out ends of the T G, the elbows K upon the ends of pipe H, and pipes connected therewith and joining in a single discharge, the whole forming a laterally and vertically adjustable spout for said tank A, substantially as herein described.

In witness whereof I hereunto set my hand.

JACKSON H. DUNLAP.
